Primary Examiner — T. Chase Nelson

(74) Attorney, Agent, or Firm — Banner & Witcoff, Ltd.

(57) **CLAIM**The ornamental design for a shoe sole, as shown and
described.**DESCRIPTION**FIG. 1 is a front perspective view of a shoe sole showing our
new design;

FIG. 2 is a bottom view thereof; and,

FIG. 3 is a rear perspective view thereof.

The broken line immediately adjacent to the shaded area
represents an unclaimed boundary of the design. The broken
lines showing the remainder of the shoe are for environmental
purposes only and form no part of the claimed design.**1 Claim, 3 Drawing Sheets**(56)
